HOLDER FOR SCISSORS OR THE LIKE

Thomas P. Morgan, 2007 Kearny St. NE.,
Washington, D.C.

Filed Oct. 27, 1958, Ser. No. 53,181

Term of patent 14 years

(Cl. D22—6)

Fig. 1 is a front elevational view of a holder for scissors or the like, showing my new design;

Fig. 2 is a side elevational view thereof; and

Fig. 3 is a front elevational view thereof as it appears with the top flap in closed position.

The dominant feature of my design resides in the narrow, laced, blade-receiving sheath in combination with an enlarged teardrop shaped flap wherein the narrower front portion overlaps the broader rear portion, all as shown.

I claim:

The ornamental design for a holder for scissors or the like, as shown and described.
